Design No. 524. —

ABBOTT and LAWRENCE, ASSIGNEES OF

Samuel H. Sailor Patented Nov. 7th 1852.

KEYSTONE

STOVE.

Fig. 2.

Fig. 3.

Dec. 524

Samuel H. Sailor of Philadelphia, Pa.

Assignor to

James G. Abbott & Archiles Lawrence of same place
Letters Patent. N° 524 Dated Nov. 9th 1852.

The schedule referred to in these Letters Patent and making part of the same

To all whom it may concern.

Be it known that I, Samuel H. Sailor, of
Philadelphia, ^{in the County of Philadelphia} and State of Pennsylvania, have invented or produced, new & original designs in the stove called "The Keystone Stove", and I do hereby declare, that the following is a full, clear, and exact description of the same; reference being had to the annexed drawings, making part of this specification, in which

Figure 1. is a front view of the stove.

Figure 2. is an end view, or side elevation.

Figure 3. is a front view of the foot of the stove.

The same letters refer to the same parts in all the figures.

The front of the stove consists of the sunken panels (e, e'), having on each the scroll ornament (a), surmounted by the flowers (b); the doors (c, c'), and the inclined fender (d).

The doors (c, c') are composed of the mouldings (f) and the raised panel (f'), upon the upper part of which, is the ornament (g) composed of foliage and fruit in bas-relief. The lower parts of the doors (c, c') are filled with the sunken panels (h) and the sliding damper (k).

Upon the inclined feeder (d) and in the sunken panel formed by the mouldings (2) is the ornament (m), formed of a rose and leaves in the centre, with scrolls at either end.

The end plate has on the exterior edge, the mouldings (m), forming the sunken panel (m'), which has a raised centre, supported by the mouldings (m''). The centre of the panel is ornamented by the vase and flowers (m''').

In the other end, the raised centre is ornamented in the same manner and is movable, forming a feeding door.

The foot is ornamented by the combination of scrolls, flowers, and foliage, the configuration of which is represented in figures³.

What I claim as my invention or production, I desire to secure by Letters Patent, is the ornamental design upon the front, ends, and feet of the stove as fully described in this specification and the accompanying drawings.

In testimony whereof I have hereunto subscribed my name before two subscribing witnesses.
